UNITED STATES PATENT OFFICE

2,457,865

TOY WAGON

Asa B. Carmichael, Tujunga, Calif.

Application December 7, 1945; Serial No. 633,413

3 Claims. (Cl. 46—107)

1

This invention relates to a toy wagon, and more particularly to a mechanical toy wagon drawn by life-like toy horses.

It is an object of this invention to provide an improved toy horse-drawn wagon with moving figures on the wagon and with means to impart movement to the horses' legs to simulate a horse-drawn wagon.

Another object of this invention is to provide an improved ambulating toy depicting a horse-drawn circus wagon which is spring-powered to cause the wagon to move mechanically along the floor in simulation of a wagon drawn by horses in a life-like manner.

It is a further object of this invention to provide a toy wagon which is spring-wound for free mechanical movement along the floor and having rotary toy figures on the wagon and movable horses which appear to draw the wagon as it moves along the floor.

It is still another object of this invention to provide a toy horse-drawn wagon having a concealed spring-operated drive for turning the wagon wheels and for causing the horses' legs to bend at the shoulders and knees in a life-like manner to give the impression that the wagon is being drawn by the horses.

Other objects of this invention will appear from the following specification and claims and from the accompanying drawings illustrating the invention, wherein:

Figure 1 is a side elevational view, partly in section, of the toy horse-drawn wagon of this invention.

Figure 2 is a fragmentary sectional detail showing the hind leg construction of the horses.

Figure 3 is a sectional view taken on line 3—3 of Figure 1; and

Figure 4 is a schematic fragmentary detail view showing the manner of operating the horses' legs.

Referring to the drawings, the body 1 of the wagon is shown as being supported by front axle 2, rear axle 3, front wheels 4, and rear wheels 5. The wheels 4 and 5 are preferably provided with rubber tires 6, although other forms of tires may be adopted.

In the preferred form of this invention the wagon is of a circus type and of ornate design including bright color combinations. Various types of figures and ornaments may be included on the wagon. As shown in Figure 1, a clown 7 is shown in the driver's seat, an elephant 8 is shown seated on a rotary pedestal 9 in the center of the wagon, and a monkey 10 is shown seated at the rear of

2

the wagon. Fixed ornamental umbrellas 11 and 12 and a rotary ornamental umbrella 13 are provided on the wagon. The front of the vehicle is provided with a wagon shaft 14 to which are suitably attached a pair of toy horses 15, a left horse and a right horse. The horses are provided with front legs 16 and hind legs 17. Harness 18 with reins 19 are provided to further simulate a horse-drawn wagon.

To create amusement and to simulate a real horse-drawn wagon, the following parts are movable during motion of the vehicle as indicated: the pedestal 9, with elephant 8 fixed thereon, rotates; wagon wheels 4 and 5 rotate; and the horses' legs 16 and 17 bend at the shoulders and knees in simulation of walking live horses. The mechanical apparatus for operating the movable parts, referred to above, are concealed within the wagon and are described as follows: within the body of the wagon is mounted a powerful clock-like spring 20 of conventional construction, wound by key 21 extending beneath the wagon. The spring 20 is connected to vertical shaft 22 so that as the spring 20 unwinds, the shaft 22, with pedestal 9 fixed thereto, rotates. The spur gear 23, fixed to shaft 22, drives a worm gear 24, fixed to horizontal shaft 25 journaled in brackets 26, fixed to the body 1. At the end of driven shaft 25 is fixed a bevel gear pinion 27 for meshing with and driving a bevel gear 28 fixed on axle 3, for driving axle 3 and the rear wheels 5. The gear 28 meshes with and drives bevel gear 29 fixed on one end of a shaft 30. The umbrella 13, fixed at the upper end of shaft 30, is thus rotated during rotation of the axle 3. The shaft 30 has one end of coil spring 31 connected thereto, the other end of the spring being connected to a tie rod 32, connected to the body 1. This structure maintains gear 29 in mesh with gear 28. The front wheels 4 rotate freely and receive rotary motion from the floor as the rear wheels drive the vehicle forward.

Each of the horses' legs is moved by opposed elastic or tension cords, one cord to cause flexion of the leg and the other cord to extend or straighten out the leg. For this purpose each foreleg is comprised of wooden leg forms 33 and 34, and each hind leg is comprised of wooden leg forms 35 and 36, the forms being appropriately shaped, as shown in Figure 1 and connected to form shoulder joints 37 and knee joints 38. The front legs are designed to flex backward and the hind legs are designed to flex forward. A number of screw eyes 39 are fastened around the edges of the leg forms and through the eyes pass the tension or elastic cords. Each hind leg is pro-

vided with an extension elastic cord 40 passing through the screw-eyes 39 along the back of the leg forms, and anchored at the top of the leg at 41 and at the bottom of the leg at 42. When this leg is bent forward at knee joint 38, the elastic cord 40 opposes this action and will tend to straighten out the leg. Similarly each front leg is provided with an extension elastic cord 43, passing through the screw-eyes 39 along the front of the leg forms, and anchored at the top of the leg at 44 and at the bottom of the leg at 45. Thus when a front leg is bent backward at knee joint 38, the elastic cord 43 opposes bending action and tends to straighten the leg. Similarly each hind leg is provided with a flection elastic cord passing through the screw-eyes along the front of the leg forms and anchored at the bottom of the leg as at 46. Also each front leg is provided with a flection elastic cord passing through the screw-eyes along the back of the leg forms and anchored at the bottom of the leg as at 47. The flection elastic cords oppose the extension elastic cords and operate to flex the legs, the front leg backwardly and the hind leg forwardly, to simulate a real horse. Each flection cord, adjacent the top of the leg, passes through an opening as 48 and 49, in the side of the horse and thence through an opening into shaft 14 and extend through the shaft 14 for connection to a driving disc in the front of the wagon, explained hereinafter. If desired the flection elastic cord may connect with an ordinary cord in the shaft 14 and form a continuation thereof, the ordinary cord being connected to the driving disc. Only the elastic cords producing flection pass through the wagon shaft 14.

As shown schematically in Figure 4, the flection cord 50 for the left horse's left hind leg is attached to a drive disc 51 at the crank pin 52. The flection cord 53 for the left horse's left front leg is attached to drive disc 54 at the crank pin 55. The flection cord 56 for the left horse's right hind leg is attached to the disc 57 at the crank pin 58. The flection cord 59 for the left horse's right front leg is attached to the disc 60 at the crank pin 61. The flection cord 62 for the right horse's left hind leg is attached to the disc 63 at the crank pin 64. The flection cord 65 for the right horse's left front leg is attached to the disc 66 at the crank pin 67. The flection cord 68 for the right horse's right hind leg is attached to the disc 69 at crank pin 70. The flection cord 71 for the right horse's right front leg is attached to the disc 72 at crank pin 73. The discs 51 and 54 are mounted on a stub shaft 74 passing through an upright post 75 fixed within the front end of the wagon. Similarly discs 57 and 60 are mounted on a stub shaft 76 passing through an upright post 77; discs 63 and 66 are similarly supported by post 78, and discs 69 and 72 are similarly supported by post 79. The use of stub shafts to support the discs permits the flection cord ends to revolve with the discs without fouling the cords on a continuous shaft. The front axle 2 has fixed thereon grooved wheels 80, 81, 82 and 83 having belts 84, 85, 86 and 87, respectively, for driving the discs 51, 57, 63 and 69, respectively, which are grooved to receive the belts.

It is thus evident that the horses' legs receive a motive force from the front wheels. As the front wheels turn, the discs 51, 54, 57, 60, 63, 66, 69 and 72 will rotate through the belts 84, 85, 86 and 87 to cause the flection cords to be pulled and released alternately. As each flection cord is pulled, the leg associated with the particular flection

cord will flex or bend at the knee. This action will tension the extension cord of that leg. Then as soon as the disc rotates sufficiently to loosen the flection cord, the extension cord will immediately straighten the leg. The position of the crank pins 52, 55, 58, 61, 64, 67, 70 and 73 are such that the four legs of a horse are flexed and straightened in a natural sequence.

In operation, the key 21 is turned to wind the 10 spring and the toy placed on the floor. As the spring unwinds, the elephant 8 and umbrella 13 will rotate, and the rear wheels 5 will be driven to move the toy along the floor. The friction between the front wheels 4 and the floor will cause the front wheels to rotate and this in turn will supply the motive power to cause the horse's legs to move in simulation of live horses and give the impression that the horses are pulling the wagon.

While a certain specific embodiment of this invention has been shown it will be understood that various modifications may be made within the spirit of the invention. Therefore no limitations on the invention are intended other than are imposed by the scope of the appended claims.

I claim:

25 1. A toy vehicle comprising a wagon including front and rear wheels, a wagon body mounted on said wheels, a shaft extending forwardly of said wagon body, at least one toy horse fixed to said shaft, said horse being provided with front and hind legs having sections forming knees and shoulder joints, a power means concealed in said wagon body for driving at least one of said wheels to move the vehicle, and means operable from said front wheels for moving the horse's legs during the movement of the vehicle to simulate a horse-drawn wagon, said means for moving the horse's legs comprising a pair of elastic members for each leg, one elastic member to flex the leg and the other elastic member to straighten the leg, and means to alternately operate the elastic members for each leg.

2. A toy vehicle comprising a wagon including front and rear wheels, a wagon body mounted on 45 said wheels, a shaft extending forwardly of said wagon body, at least one toy horse fixed to said shaft, said horse being provided with front and hind legs having sections forming knee and shoulder joints, a power means concealed in said 50 wagon body for driving at least one of said wheels to move the vehicle, and means operable from said front wheels for moving the horse's legs during movement of the vehicle to simulate a horse-drawn wagon, said means for moving the horse's legs comprising a concealed elastic cord for flexing the leg, having one end fixed to the lower end of each leg and the other end extending through said shaft, a concealed elastic cord for straightening the leg, having one end fixed to the lower end of each leg and the other end fixed to the upper end of each leg, and concealed means in the wagon body for connecting to and alternately pulling and releasing the end of said first-mentioned elastic cord extending through said shaft.

3. A toy vehicle comprising a wagon including front and rear wheels, a wagon body mounted on said wheels, a shaft extending forwardly of said wagon body, at least one toy horse fixed to said shaft, said horse being provided with front and hind legs having sections forming knee and shoulder joints, a power means concealed in said wagon body for driving at least one of said wheels to move the vehicle, and means operable from said front wheels for moving the horse's legs during movement of the vehicle to simulate a horse-

drawn wagon, said means for moving the horse's legs comprising a plurality of concealed elastic members, two for each leg, one elastic member of each pair being provided to flex the leg and the other elastic member of each pair to straighten the leg, a plurality of concealed rotating discs in the forward end of said wagon body, said discs being driven from said front wheels, each of said elastic members for flexing a leg having a crank connection with one of said discs for operation thereby, said several crank connections being relatively positioned to cause proper timed flexing of the horse's legs to simulate a walking or running horse, said straightening elastic member

operating automatically during released movement of its complemental flexing elastic member.

ASA B. CARMICHAEL.
